UNITED STATES PATENT OFFICE.

CHARLES A. CHANNELL, OF CHICAGO, ILLINOIS, ASSIGNOR TO CHANNELL CHEMICAL COMPANY, OF CHICAGO, ILLINOIS, A CORPORATION OF ILLINOIS.

DUST-MOP HEAD.

1,187,608.

Specification of Letters Patent. Patented June 20, 1916.

Application filed September 24, 1913. Serial No. 791,519.

To all whom it may concern:

Be it known that I, CHARLES A. CHANNELL, a citizen of the United States, and a resident of the city of Chicago, county of 5 Cook, and State of Illinois, have invented certain new and useful Improvements in Dust-Mop Heads; and I do hereby declare that the following is a full, clear, and exact description of the same, reference being had 10 to the accompanying drawings, and to the numerals of reference marked thereon, which form a part of this specification.

This invention relates to dust mop heads, and has for its object to provide certain improvements in that type of mop head disclosed in an application for Letters Patent filed by me Apr. 9, 1913, Serial No. 759,875, said improvements consisting, first, in novel features in the socket member for receiving 20 the handle of the mop, and secondly, in means for tightening and retaining the rod or wire which holds the mop to the mop head.

The invention (in a preferred form) is 25 illustrated in the drawings, and hereinafter more fully described.

In the drawings: Figure 1 is a top plan view of the mop head, showing the mop in dotted lines. Fig. 2 is a central section 30 taken therethrough on line 2—2 of Fig. 1, and showing the handle attached. Fig. 3 is a fragmentary detail view in top elevation showing the locking and retaining elements in release position. Fig. 4 is a fragmentary view showing the gap in the retaining flange of the mop head for the reception 35 of a locking member. Fig. 5 is a fragmentary view shown partly in section illustrating the projecting members which engage the mop fabric. Fig. 6 is an edge view 40 of one end of the mop head flange, terminating at the gap. Fig. 7 is a section taken on line 7—7 of Fig. 2. Fig. 8 is a front elevation of the locking member adapted to extend 45 across the gap in the retaining flange of the mop head.

As shown in the drawings: The mop head, 50 comprises a sheet of metal bent to afford a bottom or base 1, and a grooved flange 2, which extends almost completely around said bottom, the ends terminating at a short distance from one another, to afford a gap for the reception of the attaching or locking member 3. The attaching and locking mem-

ber 3, comprises a strip of metal provided 55 with a relatively narrow offset end 4, adapted to be inserted through the aperture 5, in one of the ends of the grooved flange 2, and having its opposite end 6, bent to conform to the curvature of the flange and of a length 60 to permit the same to be swung over the adjacent end of said flange and to be firmly engaged against the inner face of the same.

The mop comprises a plurality of fabric strands 7, which are looped over at their 65 middle and secured within a fabric covering band 8, thus affording an annular recess 9, through which is inserted a resilient steel wire or rod 10. Said wire 10, is hooked over at each of its ends 11, and 12, respectively, 70 the end 12, adapted to extend through the aperture 13, in one of the ends of the flange, and the end 11, through one of the apertures 14, in said locking member 3.

The bottom portion 1, of the mop head is 75 struck upwardly to afford slightly raised side walls 15, and as shown in Fig. 7, the walls thus formed are slotted or apertured to receive the integral downwardly extending and laterally turned ears of the cover plate 80 17 of the handle socket, to hold the same in register over the upwardly struck portion of the bottom 1. Said cover plate as shown, comprises a plate of metal which is stamped or struck to afford a curved portion, and 85 downwardly depending flanges 18, which are so formed that when the plate is secured to the bottom 1, by means of the ears 16, as has been described, said curved portion will extend obliquely upward from the bottom 90 plate, as shown in Figs. 1 and 2. Apertures or slots 19, are provided in said cover plate at a point intermediate the curved portion and the depending flanges 18, and as shown in Figs. 1, 2 and 7, a plate 20, is rigidly secured in position beneath the curved portion of the cover plate 17 by means of integral ears 21, on the same which extend through the apertures or slots 19, and secure 95 said members in rigid relation to receive a 100 handle 22, therein. The bottom portion 1, of the mop head is apertured or cut away for the sake of lightness.

As shown in Figs. 5 and 6, the flange 2, is struck outwardly at a plurality of places to 105 afford pointed members 24, adapted to engage the fabric of the mop when the same is secured in position.

The operation is as follows: When it is desired to secure the mop upon the mop head, the wire or rod 10, is threaded through the recess 9, in the mop, and the band 8, 5 of the mop is clamped into the groove of the flange 2, and engaged at the sharp points 24, by means of the wire 10, with the end 12, thereof engaged in the aperture 13, in one end of said flange 2, near the gap. The end 10 11, of the wire is then engaged in one of the apertures 14, in the locking member 3, as shown in Fig. 3. The member 3, is then turned on the offset end 4, engaged in aperture 5 of one of the ends of flange 2, as a 15 fulcrum point, and over the extremity of the walls, on the opposite side of said gap, and then downwardly. It is obvious that the pivotal movement of the locking member 3, about the fulcrum point, will draw the end 20 11 of the wire circumferentially and inwardly thus tightening the wire around the flange 2, to effectually secure the mop thereon. One of the members 17 and 20, affording the engaging means for the handle 22, is stamped 25 to afford threads whereby said handle may be threaded therein. When it is desired to clean the mop the free end of the locking member 3, is raised upwardly and permitted to swing outwardly, thereby releasing end 30 11, of said wire 10, and permitting the mop to be detached from the grooved flange wall 2, and the mop may then be washed and cleaned or replaced by a new one, as desired.

35 I am aware that details of construction may be varied through a wide range without departing from the principles of this invention, and I therefore do not purpose limiting the patent granted otherwise than necessitated by the prior art.

Copies of this patent may be obtained for five cents each, by addressing the "Commissioner of Patents, Washington, D. C."

I claim as my invention:

1. In a device of the class described, a mop head comprising a base plate, a socket cover plate comprising a curved portion provided with integral depending flanges, 45 adapted to be secured to said base plate with the curved portion arranged obliquely with respect to said base plate, and a complementally curved plate secured to said cover plate to afford a recess adapted to receive 50 a mop handle intermediate the same and the curved portion of the cover plate.

2. In a device of the class described, a mop head having a portion thereof struck upwardly, a socket cover plate therefor comprising a curved portion provided with depending flanges adapted to be secured to the base plate and in a position above the upwardly struck portion of the same, and a complementally curved plate secured to said 60 cover plate at points intermediate the curved portion of said cover plate and depending flanges thereof.

3. In a device of the class described, a mop head comprising a base plate, a cover 65 plate comprising a curved portion provided with integral depending flanges, adapted to be secured to said base plate, and a complementally curved plate secured to said cover plate to afford a recess adapted to receive 70 a mop handle intermediate the same and the curved portion of the cover plate.

In testimony whereof I have hereunto subscribed my name in the presence of two subscribing witnesses.

CHARLES A. CHANNELL.
